United States Patent Office.

JESSE HAVENS, OF AUBURN, NEW YORK.

Letters Patent No. 73,890, dated January 28, 1868.

IMPROVEMENT IN WOOD-SAW FRAMES.

The Schedule referred to in these Letters Patent and making part of the same.

TO ALL WHOM IT MAY CONCERN:

Be it known that I, JESSE HAVENS, of Auburn, in the county of Cayuga, and State of New York, have invented a new and useful Improvement in Frames for Wood-Saws; and I do hereby declare that the following is a full, clear, and exact description of the same, reference being had to the annexed drawings, making part of this specification, in which the same is shown in elevation.

The following description will enable one skilled in the art to construct the saw-frame with my improvements.

A is one end of the frame, and B the other. These pieces are respectively formed substantially as shown in the drawings, the piece B being extended below the saw to form a handle, to be grasped by one hand of the operator. C is the cross-brace, forming a fulcrum for the end pieces, which, being drawn together above, form levers for stretching the saw-blade. This brace is made of wood, as are also the pieces A and B. The brace is bifurcated at one end, so that, while the lower part extends in a right line, parallel with the saw-blade, across the frame, from the piece A to the piece B, the part C' is curved upwards, resting against the upper part of the end piece A. D is the device for tightening the saw. It is permanently attached to the end piece B by a neck and head, D³, which is inserted in a longitudinal slot of corresponding form, cut in the end of the frame-piece B, and it is secured by a collar, E, sliding neatly on to the end of the same. A screw-thread is cut upon the projecting end of the metallic piece D, which passes through holes in the piece C', and also in the piece A. A nut, D¹, is screwed on to the piece D, inside of the frame-pieces C' and A, and a nut, D², is screwed on the projecting end of the same, by which nuts the frame and saw F are held rigidly in place.

To tighten the saw, the nut D¹ must be loosened, and the rod D drawn up by the outside nut D², the nut D¹ being screwed down again, to confine the frame, as before.

What I claim as my invention, and desire to secure by Letters Patent, is—

1. A saw-frame, in which a bifurcated wooden brace, C C', constructed in one piece, as described, is used, in combination with the end pieces, substantially as described.
2. The piece D, constructed with a neck and head, D³, and used in combination with the frame-pieces A, B, and C, with which it is united, substantially in the manner and for the purpose set forth.

In testimony whereof, I have signed my name to this specification in the presence of two subscribing witnesses.

JESSE HAVENS.
